UNITED STATES PATENT OFFICE

162,244

DRESS

Samuel Skurnik, Boston, Mass.

Application April 21, 1950, Serial No. 9,393

Term of patent 14 years

(Cl. D3—26)

To all whom it may concern:

Be it known that I, Samuel Skurnik, a citizen of the United States of America and a resident of the city of Boston, in the county of Suffolk, Commonwealth of Massachusetts, have invented a new, original, and ornamental Design for a Dress, of which the following is a specification, reference being had to the accompanying drawing, forming part thereof.

Fig. 1 is a front view of a dress, showing my new design.

Fig. 2 is a back view of said dress.

Fig. 3 is a detail side view of the cuff.

I claim:

The ornamental design for a dress, substantially as shown.

SAMUEL SKURNIK.
